UNITED STATES PATENT OFFICE.

JEPHTHA COLUMBUS TATUM, OF RICHLAND, GEORGIA.

SHOE-HEEL.

1,206,051.

Specification of Letters Patent. Patented Nov. 28, 1916.

Application filed August 12, 1916. Serial No. 114,543.

To all whom it may concern:

Be it known that I, JEPHTHA C. TATUM, a citizen of the United States of America, residing at Richland, in the county of Stewart and State of Georgia, have invented new and useful Improvements in Shoe-Heels, of which the following is a specification.

The present invention relates to improvements in shoe heels, and is designed to penetrate 10 feet and improve the construction of the shoe heel shown in my allowed application for patent Ser. No. 94,706, filed May 1, 1916. In said application for patent a shoe heel is provided with a movable friction member 15 for generating heat in the heel of the shoe so that the foot of the wearer may be warmed, the friction being generated by the action of the wearer in walking.

The present invention contemplates a different and improved form of movable or friction member, and also embodies novel means for increasing the friction between the movable and the stationary friction members so that as the movable member 25 wears, the wear may be taken up and the friction preserved.

In the accompanying drawings I have illustrated this novel form of the invention constructed and arranged according to the best mode I have so far devised for the practical application of the principles of the invention.

Figure 1 is a vertical, central sectional view of a shoe heel equipped with my novel device. Fig. 2 is a top plan view of the device, detached from the heel. Fig. 3 is a horizontal sectional view on line 3—3 of Fig. 1. Fig. 4 is a top plan view of the movable friction member, detached. Fig. 5 is a top plan view of the removable bottom of the movable friction member.

For purposes of illustration I have indicated a portion of a shoe as 1, and the heel 2 is of usual leather formation, but it will be understood that heels of other material may be used in connection with my invention, it being essential that a socket or hole 3 be provided in the heel.

Within the hole 3 the stationary friction member 4 is seated, and comprises a metallic cup shaped or cylindrical member open at the top and formed with an annular projecting flange 5, perforated at 6, 6, to receive the nails or other fastenings 7 by which the stationary friction member or cup is fastened in the heel 2. This cup forms a recep-

tacle in which the movable friction member or plunger 8 is adapted to reciprocate and by its friction with the stationary cup 4, to generate heat to warm the feet of the wearer of the shoe. The plunger 8 is cylindrical and preferably of comparatively thin steel, and in order that it may be distended when required it is formed with a series of kerfs or slots 9 extending from the top to near the bottom of the plunger. The plunger is also formed with a series of diametrically arranged inclined bosses or lugs 10, 10, of a wedge shape and wider at the lower end than at the upper end.

The cup or plunger 8 is open at both ends, but a bottom plate 11 is provided to close the lower end of the cylindrical member, and is formed with an annular flange or shoulder 12 to fit up under the lower edge 76 of the plunger. This bottom plate is also provided with a perforated and screw threaded central boss 13 in which the screw 14 is threaded, and by means of the head 15 which is countersunk in the head 16 of the 80 conical or tapered shell 17, the plunger body 8, the bottom plate 11 and the shell 16 are held together, to form the movable friction member. The friction member is resiliently supported by the coiled spring 18 which is seated in the bottom of the fixed cup 4 between it and the bottom plate 11, and it will be noted that the dished formation of the plate permits of the use of a longer spiral spring than if the plate were flat, thus insuring greater resiliency for the plunger or movable friction member.

In order to ventilate the heel for summer use, I provide an opening 19 at the front face of the heel which is closed by a 95 spring plate 20 pivoted in the heel at 21. This plate may be turned to open position when desired to ventilate the heel and cool the air in the hollow heel.

It will readily be understood that the action of walking operates to warm the air in the shoe, for as the shoe heel is placed on the ground, the heel of the wearer forces the movable member or plunger down against the tension of the spring 18 which is compressed, and then when the weight of the walker is transferred to his other foot and the shoe heel raised off the ground, the spring lifts the movable member, and inasmuch as the exterior surface of the 115 movable member is in close frictional contact with the interior wall of the fixed cup

of friction member 4, heat is generated and the interior of the shoe is warmed. The plunger is preferably made of thin steel, although other materials may be used if desired, and as before stated the wear on the outer surface of the plunger may be taken up by turning the screw 14 to force the conical member 17 into the cylinder 8 in order to spread its walls. In this manner also the friction may be regulated between the two friction members, and a greater or lesser friction may be attained as desired.

From the above description taken in connection with my drawings it will be readily apparent that I have provided an improved device which will fulfil the conditions and functions of a comparatively perfect foot warmer of this character.

What I claim is:—

1. A hollow shoe heel having a cup fixed therein, a resiliently supported reciprocable member in the cup in frictional engagement with the walls of the cup, and means for varying the friction between said member and the cup, said member adapted to reciprocate as the wearer of the shoe walks.

2. A hollow shoe heel having a fixed cup, a resiliently supported reciprocable member including a slotted body portion in frictional contact with the walls of the cup, and means for varying the friction between said body portion and the cup, for the purpose described.

3.. A shoe heel having a fixed cup, a resiliently supported reciprocable member including a metallic, slotted body portion in frictional contact with the cup and lugs with inclined faces integral with said body portion, an inverted, frusto-conical shell closing the upper end of the body portion, a bottom plate for said portion, and a screw connecting these portions whereby the friction between the body of the member and the cup may be varied.

In testimony whereof I affix my signature: JEPHTHA COLUMBUS TATUM.
